UNITED STATES PATENT OFFICE.

HAROLD E. HALE, OF SOMERVILLE, MASSACHUSETTS, ASSIGNOR TO TUNERS' SUPPLY COMPANY, OF SOMERVILLE, MASSACHUSETTS, A CORPORATION OF MASSACHUSETTS.

TUNING-HAMMER.

1,160,107.

Specification of Letters Patent.

Patented Nov. 9, 1915.

Application filed August 13, 1914. Serial No. 856,515.

To all whom it may concern:

Be it known that I, HAROLD E. HALE, a citizen of the United States, and resident of Somerville, county of Middlesex, Commonwealth of Massachusetts, have invented an Improvement in Tuning-Hammers, of which the following description, in connection with the accompanying drawings, is a specification, like characters on the drawings representing like parts in each of the several views.

This invention relates to appliances for tuning pianos and like instruments, of the type known as tuning hammers, these being more properly a form of wrench adapted to engage and turn the squared or angular ends of the piano pins. In this type of appliance it is requisite to form the wrench head separate from the handle shank, with an extension adapted to hold the socket piece extending out laterally in a somewhat oblique direction from the handle, and a connection to the handle capable of holding the parts rigid and secure in use and of such a nature as to withstand and transmit heavy torsional and angular stresses and thrusts.

A prime object of the present invention is to form a tuning hammer wrench head with a connection to its handle shank that is exceptionally strong and rigid, yet capable of being readily assembled and taken apart. To this end I provide a novel construction of cone and cup interengagement between the handle shank and the wrench head co-operative with a bolt and nut connection to hold the parts together but little less rigidly and securely than as though they were integral.

The above and other objects and features of the invention will be better understood from the following detailed description taken in connection with the accompanying drawings and will be thereafter pointed out in the appended claims.

Referring to the drawings: Figure 1 shows in perspective a tuning hammer constructed in accordance with my invention, a part of the handle being broken away; Fig. 2 shows enlarged partly in elevation and partly in lengthwise section the interengaging parts of the wrench head and handle shank; and Fig. 3 is a view showing the same parts in elevation and separated.

The handle of the tuning hammer is indicated at 10 with a handle shank 11 that may

be extensibly mounted as is usual. The handle shank 11 has at its end a cup formation 12 and within the same a threaded nipple 13 which as shown extends a distance beyond the same. The inner walls of the cup 12 are conical as seen at 14 and are formed to fit a cone 15 projecting from the wrench head 16, this head having a threaded bore 17 extending through the cone 15 to near the back of the head and adapted to receive the threaded nipple 13. A lateral extension 18 of the wrench head may have removably fitted thereto a socket piece 19 having in the end thereof a socket recess 20 adapted to fit the ends of the pins. I preferably form slots or saw-cuts 21 lengthwise of the cone 15 whereby some little degree of resiliency is imparted thereto. Thus as the parts are assembled together, as the conical cup walls 14 engage the cone 15, the cone will in the further setting up be sprung down on to the threads of nipple 13 effecting a strong and secure locking of the parts together.

It will be noted that with my improved construction a very material reinforcing is obtained at the joint between the wrench head and the handle shank for the reason that when the parts are set up to operative locked position there is a cross section of metal to resist breakage or distortion which includes the nipple 13, the cone 15 and also the cross section through the cup 12, these several sections of metal acting virtually as an integral mass when interengaged in operative position as seen in Fig. 2. It is to be noted that this desirable result follows essentially from the fact that the cup and cone are superposed upon the same section of the connection that contains the threaded interengagement of nipple 13 in its tapped bore 17; *e. g.*, this result of reinforcing and strengthening the joint would not follow in the same way were a cone similar to the cone 15 formed at the back of the nipple 13 to engage a cup on the wrench head back of nipple 13.

I am aware that the invention can be embodied in other specific forms as to details of construction without departing from the spirit or essential attributes thereof and I therefore desire the present embodiment to be shown as illustrative and not restrictive, referring rather to the appended claims to indicate the scope of the invention.

Having described my invention, what I

claim as new and desire to secure by Letters Patent is:

1. A tuning hammer, comprising a wrench head and a handle shank, one of said members being formed with a threaded nipple and a conical cup surrounding the same at its end, and the other member having a threaded bore to receive said nipple with a cone formation through which said bore extends to fit the conical walls of said cup, said conical cup co-acting with said cone formation to constitute a reinforce superposed on the threaded connection of said nipple with said bore to resist bending and wrenching strains.
2. A tuning hammer, comprising a wrench head and a handle shank, said head having a cone formation projecting therefrom with a threaded bore extending through the cone toward the back of the head, and said handle shank having a threaded nipple at its end for engaging said bore with a conical cup surrounding said nipple and adapted to interfit with said cone as the parts are assembled, said conical cup co-acting with said cone formation to constitute a reinforce super-

posed on the threaded connection of said nipple with said bore to resist bending and wrenching strains.

3. A tuning hammer, comprising a wrench head and a handle shank, one of said members having a threaded bore with a cone extending therefrom through which said bore extends, said cone being slotted lengthwise, and the other member having a threaded nipple at its end with a conical cup surrounding said nipple and adapted to interfit with said cone as the parts are assembled to spring the same and press it into frictional locking engagement with said nipple, said conical cup co-acting with said cone to constitute a reinforce superposed on the threaded connection, to strengthen the same and resist bending and wrenching strains.

In testimony whereof, I have signed my name to this specification, in the presence of two subscribing witnesses.

HAROLD E. HALE.
